US00D571548S

(12) **United States Design Patent**
Seamans

(10) **Patent No.:** **US D571,548 S**
(45) **Date of Patent:** **** Jun. 24, 2008**

(54) **FOOTWEAR**

(75) Inventor: **Scott Seamans**, Boulder, CO (US)

(73) Assignee: **Crocs, Inc.**, Niwot, CO (US)

(**) Term: **14 Years**

(21) Appl. No.: **29/251,383**

(22) Filed: **Jan. 6, 2006**

(51) **LOC (8) Cl.** **02-99**

(52) **U.S. Cl.** **D2/971; D2/925**

(58) **Field of Classification Search** **D2/896, D2/897, 900, 925-942, 971; 36/1, 1.5, 11.5, 36/9 R**

See application file for complete search history.

(57) **CLAIM**

The ornamental design for footwear, as shown and described.

DESCRIPTION

FIG. 1 is a front perspective view.

FIG. 2 is a front view.

FIG. 3 is a back view.

FIG. 4 is an outer side view.

FIG. 5 is an inner side view.

FIG. 6 is a top view; and,

FIG. 7 is a bottom view.

The broken line showing of the sole and surface treatment thereof is for illustrative purpose only and forms no part of the claimed design.
